PHOTOGRAPHIC DISK

Filed Dec. 17, 1927

UNITED STATES PATENT OFFICE

DAVID A. McCOWAN, OF TORONTO, ONTARIO, CANADA

PHOTOGRAPHIC DISK

Application filed December 17, 1927. Serial No. 240,801.

The principal objects of this invention are, to devise a photographic disk in which the sensitized surface is surrounded by a raised rim which protects it from being marred and which serves effectively in the production of the photograph as a means for retaining the developing solution in contact with the sensitized surface and also as a protecting or holding element for a mirror surface on the 10 reverse side of the disk.

The principal features of the invention consist in the novel construction of a sheet metal disk whereby a photographic or reflecting surface is surrounded by a raised beaded edge 15 flange and said flange may be utilized to embrace and secure a supplementary disk on the reverse side of the photographic surface.

In the drawings, Figure 1 is front plan view of my device.

20 Figure 2 is a plan view of the reverse side of the disk.

Figure 3 is a cross sectional view.

This invention has been particularly devised for use in automatic photographing 25 machine and it consists of a disk of thin sheet metal preferably non-corrosive which is stamped with a central circular depressed portion 1 which may be slightly convexed as shown to add strength and to enhance the 30 appearance. The raised perimeter 2 is curled in toward the back of the disk to form a beaded edge 3.

The raised portion 2 extends above the 35 raised centre of the convexed portion 1 forming a rim which will retain a developing fluid so as to cover the central depressed area and it also forms an effective protecting flange to keep the central area from contact with other surfaces such as the sides of a bag or the lining of a pocket, thus retaining the surface on 40 which a photograph is produced from being marred.

The reverse side of the disk is preferably 45 covered with a disk 5, the edge 4 of which is flanged to fit snugly around the edge of the

depressed portion 1 and this disk is rigidly secured in place by the inturned edge of the bead 3. The outer surface of the disk 5 is arranged below the plane of the outer surface 6 of the bead 3 and it is thus protected in a 50 manner similar to the surface of the portion 1.

The disk 5 may be formed of a suitable non-corrosive metal which will take a high polish or a silvered glass disk may be used instead 55 of a metal disk.

It may be found desirable to utilize the depressed surface 1 as a mirror and the surface of the disk 5 as a photographic surface. In either case the metal surface is coated with a sensitive photographic material which after 60 being properly exposed to light through a photographic lens, may be developed by placing a small quantity of developing fluid thereon, said fluid being retained by the flanged bead surrounding same. 65

The disk in being used in an automatic machine presents a strong and rigid edge to co-operate with the automatic mechanism.

The article when completed presents a very attractive appearance and may be carried for 70 a considerable time without being marred.

What I claim as my invention is:—

1. A photographic disk formed of sheet metal having the marginal edge portion displaced from the plane of the disk, and a rigid 75 bead formation formed at the outward edge extremity of said displaced marginal edge portion.

2. A photographic disk formed of sheet metal having a laterally flanged perimeter 80 terminating in a rolled edge, and a central sensitized plane portion offset from the flanged portion to a point intermediate of the depth of the rolled portion.

3. A photographic disk formed of polished 85 sheet metal having a central circular portion of convexed form, a laterally offset flange formed with a beaded edge extremity, and a circular disk having its edge secured under the edge of said beaded flange and having a 90

sensitized plane surface disposed out of alignment with the edge of the bead formation at its point of contact with said circular disk.

4. A photographic disk formed of sheet metal having the marginal edge portion displaced laterally to one side out of alignment with the surface to be sensitized, the outward edge portions of said marginal edge portion being rolled inwardly to bring the edge thereof into close contact with the marginal edge portion on the sensitized side of the disk and out of alignment with the latter.

DAVID A. McCOWAN.
